(57) **CLAIM**

The ornamental design for a fish tail lift anchor for precast concrete, as shown and described.

DESCRIPTION

FIG. 1 is a front elevation view of the fish tail lift anchor for precast concrete showing my new design;

FIG. 2 is a rear elevation view thereof;

FIG. 3 is a right side elevation view thereof;

FIG. 4 is a left side elevation view thereof;

FIG. 5 is a top plan view thereof; and,

FIG. 6 is a bottom plan view thereof.

1 Claim, 2 Drawing Sheets
